Attorney

UNITED STATES PATENT OFFICE.

EMIL MORBERG, OF OSLO, MINNESOTA.

COLTER.

Application filed January 23, 1926. Serial No. 83,270.

The present invention relates to a colter which functions as a knife in conjunction with a plow, and is designed to take the place of the ordinary rolling colter so commonly used on plows. The present device has all the advantages of the rolling colter and the old standing colter, in that it can be manufactured cheaply, and has less parts to wear.

10 The greatest advantage of my invention, which I have found from actual practice, is that it will not fill up with mud or straw, or lift up the plow because of sticks or wood or stones.

15 With the ordinary rolling colter and old standing colter, it is practically impossible to do any plowing in sticky soil, whereas with my improved colter, the same works efficiently with a minimum amount of trouble regardless as to whether or not the soil is wet or dry.

20 By the substitution of this improved colter, for the rolling colter on the usual standard of the rolling colter, it is possible to adjust my improved colter, toward or away from the plow as may be desirable.

25 Another very important object of the invention is to provide a colter of this nature which is strong and durable, one which is thoroughly reliable, easy to manipulate, and otherwise well adapted to the purpose for which it is designed.

With the above and numerous other objects in view as will appear as the description proceeds, the invention resides in certain details of construction as will be hereinafter more fully described and claimed.

In the drawing:

Figure 1 is an elevation of the colter showing the same attached to the colter standard of an ordinary plow beam, and

Fig. 2 is a perspective view of my improved colter.

Referring to the drawing in detail, it will be seen that 5 designates a plow beam having the usual bracket 6 thereon for adjustably receiving the rolling colter standard

7. My improved colter is disposed on the lower end of this standard 7 as is clearly shown in Fig. 1.

Referring to the colter specifically, it will be seen that the same includes a blade 8 having an upper edge 9 rectangularly disposed to a rear vertical edge 10. A bottom sharpened edge 11 is shorter than the upper edge 9. A front diagonally disposed sharpened edge 12 merges into the bottom edge 11. After the upper portion of the blade 8 there is provided a strap extension which is curved or rolled to form a sleeve 13 which terminates in an extension 14, riveted as at 15 to the blade body 8. The sleeve 13 receives the lower end of the standard 7 held in place by washers 16 and pin 17 or in any other suitable manner.

The colter, therefore, is free to swing laterally by readily freeing itself from sticky soil and from sticks and stones, so as to prevent the raising of the plow when in operation. It is thought that the construction, operation, and advantages of my invention will now be clearly understood without a more detailed description therefor.

It is desired, however, to point out that the colter is exceedingly inexpensive to manufacture because of its simple construction, and is strong and durable, besides possessing increased efficiency over colters heretofore used.

Having thus described my invention, what I claim as new is:—

A colter of the class described designed for use on plows having a colter standard, comprising a blade body having an upper straight edge, a rear straight edge disposed at right angles to the upper straight edge, a bottom straight edge disposed at right angles to the rear straight edge and sharpened, and merging into a diagonally extending forward curved edge which is sharpened, and a strap merging from the upper forward portion of the blade body and bent to form a sleeve terminating in an extension riveted to the blade body, the upper edge of the strap being co-planer with the upper straight edge.

In testimony whereof I affix my signature.

EMIL MORBERG.
